UNITED STATES PATENT OFFICE.

ADONIS GEORGE EDWARD LOWMAN, OF WINNIPEG, MANITOBA, CANADA.

CARD-SCORER.

1,299,489.

Specification of Letters Patent.

Patented Apr. 8, 1919.

Application filed March 1, 1917. Serial No. 151,779.

To all whom it may concern:

Be it known that I, ADONIS GEORGE EDWARD LOWMAN, of the city of Winnipeg, in the Province of Manitoba, Canada, have invented certain new and useful Improvements in Card-Scorers, of which the following is the specification.

The invention relates to improvements in card scorers and one of the important objects of the invention is to construct an ordinary card box so that it can be utilized for scoring purposes, while another is to arrange a scorer which can be utilized for keeping the count of a great variety of card games.

A further but less important object is to provide a cheap, efficient scorer as part of the card box which will not materially increase the cost of production of the box.

With the above objects in view the invention consists essentially in the arrangement and construction of parts hereinafter more particularly described and later pointed out in the appended claim, reference being had to the accompanying drawing in which:

Figure 1 represents a perspective view of a card box constructed in accordance with my invention.

Fig. 2 represents a vertical cross sectional view through the box.

In the drawing like characters of reference indicate corresponding parts in each figure.

1 represents the ordinary rectangular cardboard card box having one end closed as shown at 2 and the other end provided with a closure flap 3. This box is utilized at the present time to receive the ordinary pack of playing cards. Actually the interior dimensions of the box are such that it will just nicely contain the pack of cards.

In playing a great variety of card games it has been customary to employ separate score pads for keeping the count. There are a few exceptions to this where wood boxes are made to contain the cards and the boxes are constructed so that a special count can be kept, such as, say for the game of "cribbage." However the latter particular card box is adapted especially for scoring the one game, not for keeping score of a variety of games.

According to my invention the ordinary cardboard box is utilized for keeping the count after the cards have been removed for

playing purposes. To accomplish this end I perforate the box as indicated generally by the reference numeral 4 and utilize pins or pegs 5 for keeping the count. It will be obvious that once the cards are withdrawn from the box that the perforations are holes, will admit the pegs and retain them so that a proper score can be indicated. This feature of perforating the cardboard card box of itself for keeping the score is considered by me as a new idea although it is herein admitted that the idea of utilizing a separate and specially perforated box with pins has been used for some time.

The perforations or holes which I make in the box are placed in definite fixed positions so that they can be used for keeping the score of a great variety of games. The special arrangement of the perforations is now described.

Up the center and running lengthwise of the box I provide a series of openings 6, these being numbered, in the present instance consecutively, and from the ends of the box inwardly 1, 2, 3, 4, 5, 6, 7. At the center of the box I place the word "Games" and in view of this name the center series of numbers are considered as game numbers. At the right and left hand sides of the box I locate further scoring numbers, there being a set of these for each player, those on the right side being utilized by one player and those on the left hand by the other and in connection with the numbering and writings on the box, it is to be understood that these are made for easy reading for the respective players sitting opposite. On each side of the game numbers I locate nine horizontal rows of perforations 7 with four holes or perforations in each row and the rows are numbered consecutively 1, 2, 3, 4, 5, 6, 7, 8, 9 with each perforation in the row bearing its particular designating number. These holes are used for keeping the initial count.

Directly above these rows of numbers I locate nine holes indicated generally by the reference numeral 8 and numbered 1 to 9 consecutively and these holes are utilized to indicate hundreds. Above the latter holes I arrange a horizontal row of perforations indicated generally by the reference numeral 9 and numbered 1 to 4 consecutively which are utilized to indicate thousands and immediately at the top of the box I place a fur-

75

100

110

ther horizontal row of four perforations 10 which are numbered consecutively 1 to 4 and are utilized to count what is known as "rubbers" in the game of "bridge." Between the 5 two top rows of figures I place the word "Bridge" and at the top of the box the word "Rubbers" and I further color the box so that the perforations indicating thousands and those indicating "rubbers" will appear on a 10 background distinct from the other perforations.

At the bottom of the box and for each player I locate a single right hand perforation indicated at 11 and a single right hand 15 perforation indicated at 12, the perforation 11 being utilized as a zero hole while the perforation 12 is used for indicating a minus score such as occurs in the game "five-hundred." Preferably I circumscribe this latter 20 hole 12 with a circle and color the interior of the circle a different color from that of the box.

The rows of initial count perforations are divided by a centrally located divisional line 25 13 for a purpose shortly described.

The above described scorer can be utilized for scoring practically all card games including that of "bridge" and "five-hundred" which are more or less irregular. In utilizing 30 the box for the ordinary card games wherein the score progresses regularly from one up to whatever score determined upon as a "game" I utilize the rows of initial count perforations to keep the score and these perforations will accommodate any score from 35 1 to 9999. If it is desired to carry the score higher than this, one can tab the thousands in the holes 9 which indicate thousands. It will be readily understood that each time a 40 game is scored one places a peg in the game holes 6.

To utilize the score for "five-hundred" the score is counted in the usual way as just indicated and any minus count is indicated by 45 marking the score with the pegs and then inserting a further peg in the hole 12 to indicate that the score marked is a minus or negative one.

In utilizing the score for keeping a 50 "bridge" score one counts the points on the

right hand side of the line 13 and the honors on the left hand side of the line 13. The honors and points are added together from time to time and carried ahead by placing a peg in one or other of the holes 8 indicating 55 hundreds, and carrying the remainder of the score in the right hand initial score perforations 7. The score can be further carried in the same way into the thousands by utilizing a peg in the thousands hole perforations 9. 60 Each time one scores a game he indicates this by placing a peg in the game perforations 6 and each time he scores a "rubber" he indicates it by placing a peg in one of the "rubber" holes 10.

From the above it will be obvious that my particular arrangement of perforations is an important one as it allows of the keeping of the score for practically all ordinary games as well as the more difficult scoring as required in the game of "bridge."

What I claim as my invention is:—

As a new article of manufacture, a cardboard box having a series of centrally arranged, lengthwise extending, consecutively numbered perforations, therein indicating games, horizontal rows of perforations at opposite sides of the game-perforations and numbered consecutively from 1 to 9, there being four perforations in each row, a series of 80 consecutively numbered perforations above the ninth row of horizontal perforations in each instance and indicating hundreds, a series of consecutively numbered perforations above the latter perforations and indicating 85 thousands, a series of consecutively numbered perforations above the latter perforations and indicating "rubbers", a divisional line passing lengthwise of the box at each side and centrally between the horizontal 90 rows of perforations and a single designated perforation at each end of the box indicating a negative score.

Signed at Winnipeg, this 8th day of January, 1917.

ADONIS GEORGE EDWARD LOWMAN.

In the presence of—
G. S. BOXHUND,
ROLAND FOSTER.
